PHOTOGRAPHIC FIXATIVE COMPOSITION
CONTAINING BORIC ACID ESTERS OF
POLYHYDRIC ALCOHOLS OF AT LEAST SIX
CARBON ATOMS

Charles Holzwarth, Parlin, N. J., assignor, by
mesne assignments, to E. I. du Pont de Ne-
mours & Company, Wilmington, Del., a corpo-
ration of Delaware

No Drawing. Application April 10, 1941,
Serial No. 387,976

16 Claims. (Cl. 95—88)

This invention relates to photographic compositions and more particularly to photographic fixing solutions. Still more particularly it relates to photographic fixing compositions in a highly concentrated form and to the preparation and use thereof.

Photographic fixing solutions in concentrated form are known, but they have various disadvantages, the major one being that the dissolved essential ingredients crystallize out of solution during storage or shipment. This is particularly noticeable when they are subjected to temperatures below 20° C.

An object of this invention is to provide a practical photographic fixing solution in concentrated form. Another object is to provide a concentrated photographic fixing solution, the ingredients of which remain in solution over a wide range of temperature conditions. Yet another object is to provide stabilizing agents which will inhibit crystallization and/or precipitation in highly concentrated photographic fixing solutions. A further object is to provide agents which have a stabilizing effect on concentrated photographic solutions, but do not have an adverse effect on the photographic functions of such solutions. A still further object is to provide new processes of stabilizing concentrated photographic solutions against precipitation of dissolved ingredients. Still further objects are to provide new uses for soluble borates of polyhydric alcohols containing at least 6 carbon atoms in the organic radical or radicals attached to the borate radical and the water-soluble salts thereof.

The above-mentioned disadvantages can be overcome and the above objects attained by the use of boric acid esters of polyhydric alcohols containing at least 6 carbon atoms in photographic fixing compositions. To be more specific, it has been found that photographic fixing compositions containing water-soluble salts of thiosulfuric acid as the fixing agents can be improved by the addition of a boric acid ester of a polyhydric alcohol containing at least 6 carbon atoms including the neutral esters, acid esters and water-soluble salts of acid esters.

In a more limited sense, the invention involves the preparation and use of photographic fixing compositions comprising a saturated or super-saturated solution of a soluble salt of thiosulfuric acid and an amount of a boric acid ester of an aliphatic polyhydric alcohol containing at least 6 carbon atoms in a straight chain and at least 6 hydroxyl groups including the neutral es-

ters, acid esters and the alkali metal and ammonium salts of acid esters.

The concentrated photographic fixing baths hereof can be prepared by admixing the thiosulfate in an amount sufficient to form a concentrated solution and stabilizing amounts of the aforescribed boric acid ester compounds. In a preferred procedural aspect, a concentrated photographic fixing bath is prepared by dissolving a quantity of a boric acid ester of a polyhydric aliphatic alcohol of at least 6 carbon atoms, in a saturated or supersaturated solution of a soluble thiosulfate fixing agent. The solution may be made facile by the aid of a moderate amount of heat, e. g. temperatures of 50 to 100° C., and agitation.

Another practical way of making the concentrated photographic fixing baths comprises warming a concentrated aqueous solution of the dried thiosulfate or mixture of thiosulfates and adding it to a vessel containing the predetermined quantity of the boric acid ester compound derived from a polyhydric alcohol containing at least 6 carbon atoms.

The solution may then be augmented by the addition of other common ingredients of fixing compositions, e. g. anti-staining, hardening and/or preserving agents, acids, etc. Among the latter agents mention might be made of soluble sulfites, e. g. alkali metal, ammonium, substituted ammonium, and amine sulfites, alums, organic acids and easily hydrolyzable salts, sulfamic acids and other materials which have been added to increase the life, penetration and usefulness of photographic fixing solutions.

It has been found that solutions prepared as described above are remarkably stable and are not subject to the expected crystallization or precipitation of dissolved solids which usually occurs when such solutions are cooled. This stability is not impaired by storage or agitation, even at reduced temperatures over a considerable period of time; and such solutions were found to fill all the requirements of a concentrated liquid fixer. As crystallization and precipitation follows rapidly in superstaturated solutions such as have been described free from the novel boron compounds hereof, it may be supposed that such compounds of polyhydric alcohols act as crystallization inhibitors.

The invention may be used with any salt of thio-sulfuric acid which has photographic fixing properties and indeed in any type of fixing solution, wherein a thiosulfate is an essential fixing agent. Thiosulfates which may be conveniently

used with the novel stabilizing boron compounds hereof include (1) alkali metal thiosulfates, e. g. lithium, sodium and potassium thiosulfates, (2) ammonium and substituted ammonium thiosulfates and (3) organic amine salts of thiosulfuric acids, including those of primary, secondary, tertiary and cyclic amines, and (4) amidine thiosulfates, etc.

The boric acid esters and alkali metal and ammonium salts used in accordance with the teachings of this invention may be prepared by reacting at least about one mol of a polyhydric aliphatic alcohol containing at least 6 carbon atoms with 1 mol of a boric acid in an aqueous medium and heating the mixture until two mols of water are lost. The alkali metal and ammonium salts can be made by the addition thereto of alkalies such as ammonia, ammonium hydroxide, sodium hydroxide, potassium hydroxide, lithium hydroxide, etc.; or the required amount of an alkali metal borate can be substituted for the boric acid in the reaction mixture.

While satisfactory results are obtained with the boric acid ester free from salt groups, it has been found that improved results can be obtained with the alkali metal and ammonium salts of such borates and still further improved results obtained from the alkali metal and ammonium salts of boric acid esters of hexahydric alcohols or hexitols.

When referring to salts of polyhydric esters such as sodium mannitol monoborate, sodium sorbitol monoborate, etc., it is understood that such terminology is used to describe any polyhydric ester that has been partially or entirely reacted with an alkali metal hydroxide or ammonia. In such cases the substance is frequently a mixture of the original boric acid ester of the polyhydric alcohol and the sodium salt of such an ester. This is usually the case because the practice is to add just enough of the alkaline material to give a solution with a pH of 7. At this pH reading, only part of the original ester is converted to the salt. The preparation of suitable boric acid esters, including the salts is more fully described in U. S. Patents 2,223,349, 2,223,948, 2,223,949 and 2,224,011 and British Patent 511,641.

The proportions of ingredients can, of course, be varied over a wide range. It has been found that concentrated fixing solutions which contain not less than 60% by weight of active fixing bath ingredients can be effectively stabilized against precipitation or recrystallization of dissolved ingredients by incorporating therein not less than 8% of a boric acid ester of a polyhydric alcohol of at least 6 carbon atoms including the alkali metal and ammonium salts of such esters.

The invention will be further illustrated, but is not intended to be limited by the following examples. In each example the thiosulfate salt is first dissolved in about half its own weight of water at a temperature somewhat above 50° C. and then the organic borate is dissolved in the resulting solution. After thorough incorporation of the borate, the remaining ingredients are each added in the order in which they appear in the formulae and dissolved with vigorous stirring. If difficulty is experienced in dissolving these latter constituents they may be dissolved in a minimum of warm water before adding to the solution. The final volume of the concentrated fixer is brought in each case to a volume of 1000 ml. by concentration or dilution, de-

pending on the type of adjustment the formula requires.

Example I

5	Ammonium thiosulfate (anhydrous)	grams	570
	Sodium sorbitol monoborate (pH 7)	do	125
	Sodium sulfite (desiccated)	do	30
	Acetic acid (glacial)	do	10
10	Potassium alum	do	50
	Potassium metabisulfite	do	5
	Water to make	milliliters	1000

Example II

15	Ammonium thiosulfate (anhydrous)	grams	590
	Potassium mannitol monoborate (pH 7)	grams	590
	do	160	
20	Sodium sulfite (desiccated)	do	50
	Acetic acid (glacial)	do	55
	Sodium metabisulfite	do	5
	Water to make	milliliters	1000

The above bath when diluted with 3 liters of water can be successfully used in conjunction with a 3% chrome alum stop bath.

Example III

30	Ammonium thiosulfate (anhydrous)	grams	600
	Ammonium mannitol diborate (pH 7)	grams	600
	do	110	
35	Potassium sulfite (anhydrous)	do	65
	Propionic acid	do	60
	Potassium alum	do	60
	Sodium metabisulfite	do	5
	Water to make	milliliters	1000

Example IV

40	Triethanolamine thiosulfate	grams	550
	Sodium sorbitol monoborate (pH 7)	do	125
	Ammonium sulfite	do	40
45	Sodium metabisulfite	do	8
	Citric acid	do	10
	Potassium alum	do	55
	Water to make	milliliters	1000

Example V

50	Ammonium thiosulfate (anhydrous)	grams	560
	Ammonium dulcitol monoborate (pH 7)	grams	560
	do	130	
55	Sodium sulfite (desiccated)	do	40
	Potassium bisulfate	do	20
	Citric acid	do	10
	Formaldehyde	do	40
60	Water to make	milliliters	1000

Example VI

65	Ammonium thiosulfate (anhydrous)	grams	580
	Sodium mannitol monoborate (pH 7)	do	100
	Sodium sulfite (desiccated)	do	55
	Sodium metabisulfite	do	10
70	Lactic acid	do	75
	Water to make	milliliters	1000

This concentrated fixer may be diluted for use by adding to it 3000 milliliters of water to which have been added 65 grams of $\text{AlCl}_3 \cdot 6\text{H}_2\text{O}$.

Example VII

Guanidine thiosulfate	grams	565
Ammonium sorbitol monoborate (pH 7)	do	105
Sodium sulfite (desiccated)	do	40
Acetic acid (glacial)	do	35
Potassium alum	do	60
Water to make	milliliters	1000

Example VIII

Ammonium thiosulfate (anhydrous)	grams	570
Mannitol monoborate (acid)	do	200
Sodium sulfite (desiccated)	do	55
Propionic acid	do	60
Potassium alum	do	65
Sodium metabisulfite	do	5
Water to make	milliliters	1000

Example IX

Sodium thiosulfate (crystalline)	grams	850
Sodium sorbitol borate (pH 7)	do	125
Ammonium sulfite	do	40
Potassium metabisulfite	do	10
Citric acid	do	10
Water to make	milliliters	1000

This concentrated fixer may be diluted for use by adding to it 3000 milliliters of water to which have been added 65 grams of $\text{AlCl}_3 \cdot 6\text{H}_2\text{O}$.

Example X

Potassium thiosulfate (monohydrate)	grams	680
Sodium mannitol borate (pH 7)	do	220
Triethanolamine sulfite	do	65
Potassium metabisulfite	do	10
Sodium acetate	do	40
Acetic acid (glacial)	do	40
Water to make	milliliters	1000

This concentrated fixer may be diluted for use with a solution of 70 grams of potassium alum dissolved in a sufficient quantity of water to make 3000 milliliters.

Example XI

Ammonium thiosulfate (anhydrous)	grams	500
Sodium sorbitol monoborate (pH 7)	do	80
Sodium sulfite (desiccated)	do	30
Acetic acid (glacial)	do	15
Sodium metabisulfite	do	5
Water to make	milliliters	1000

This solution may be diluted for use by the addition of 3000 milliliters of water to which have been added 60 grams of $\text{AlCl}_3 \cdot 6\text{H}_2\text{O}$.

In place of the specific boric acid esters set forth in the above examples may be substituted a large number of equivalent boric acid esters having the characteristics above set forth. The boric acid esters of the respective examples can be interchanged in any desired manner. One or more of the esters mentioned above can be used in each example. In addition, one or more of each of the boric acid esters hereof can be substituted in each of the above examples.

Additional suitable boric acid esters include the neutral and basic alkali metal or ammonium salts of the condensation products of boric acid compounds with 1,2,3,4,5-pentahydroxy hexane; heptahydric alcohols, e. g. perseitol and volemitol; octahydric alcohols, e. g. octahydroxy-octanes; nonahydric alcohols, e. g. nonahydroxy nonane, etc. These compounds and others which are described in the above-cited patents, are useful in

accordance with the teachings hereof. In general, at least 8% by weight of the compounds is necessary in concentrated fixing compositions containing not less than 60% by weight of active fixing bath ingredients for satisfactory results. Amounts from 8 to 50% constitute a practical range. The boric acid esters described herein can be used in dry fixative compositions which can be diluted to form concentrated fixing solutions or fixing baths.

Similarly, in place of the specific thiosulfates mentioned in the above examples, may be substituted one or more other water-soluble thiosulfates including alkali metal, ammonium and substituted ammonium thiosulfates. The sulfites of the examples can be interchanged in any desired manner.

A large number of suitable substituted ammonium thiosulfates and their preparation is described in a copending application of Martin Marasco, entitled "Preparation of Ammonium Thiosulfates and Uses Thereof", Serial No. 390,980 filed upon an even date herewith. These substituted ammonium thiosulfates have the general formula:

wherein R , R_1 , R_2 , and R_3 constitute members of the group consisting of hydrogen and hydrocarbon radicals, wherein two to three of the R 's may constitute a single mono- to trivalent hydrocarbon radical. To be more specific, R , R_1 , R_2 , and R_3 may constitute a hydrogen atom or a hydrocarbon radical or two or more of the R 's together form a carbocyclic hydrocarbon radical or a heterocyclic hydrocarbon radical with the nitrogen atom. Thus, one or more of R , R_1 , R_2 and R_3 may be primary, secondary, tertiary, iso or branched chain alkyl radicals of 1 to 20 and more carbon atoms; cycloalkyl of 3 to 6 and more carbon atoms, which may contain hydrocarbon and other substituents in the carbocyclic ring; aryl of 6 or more carbon atoms; aralkyl of 7 or more carbon atoms, and R and R_1 may form a cycloalkyl radical or aryl radical or a part of a chain which with the nitrogen atom forms a heterocyclic radical.

Suitable alkyl radicals for the values of R , R_1 , R_2 , and R_3 are methyl, ethyl, propyl, isopropyl, normal, primary, secondary and tertiary-butyl, -pentyl and -hexyl, 2-ethyl, hexyl, n-decyl, n-dodecyl, n-tetradecyl, n-octadecyl, etc. Suitable cycloalkyls include cyclopropyl, cyclobutyl, cyclopentyl, cyclohexyl, methylcyclohexyl, dodecylcyclohexyl, chlorocyclohexyl, etc. Suitable aryls include phenyl, chlorophenyl, tolyl, xylyl, naphthyl, chloronaphthyl, etc., and aralkyls include benzyl, chlorobenzyl, menaphthyl, etc. However, at least one hydrocarbon radical must be attached to the pentavalent nitrogen atom.

Such substituted ammonium thiosulfates and organic amine salts of thiosulfuric acid are advantageously prepared by the action of sulfur dioxide on a polysulfide of an ammonium or organic amine base in the presence of an excess of the free hydroxide of the particular ammonium or amine radical whose thiosulfate is desired. Sufficient sulfur dioxide is employed to consume entirely the sulfide ions in the original solution, and the reacting mixture must be maintained in a slightly alkaline condition throughout the entire course of the reaction.

Various other ingredients of photographic fixing compositions may be utilized in compositions similar to the above. Thus, boric acid, borax, citric acid, sodium citrate, sodium acetate, sodium amino acetate, etc., which yield borate, citrate, acetate, amino acetate, etc., ions, other acidic compounds which yield such ions may be used in place thereof or in admixture therewith. As further examples of suitable compounds, mention is made of sodium metaborate, potassium tetrahydrodiborate, sodium hexahydrotetraborate as well as other water soluble, particularly alkali metal salts of the oxygen acids of boron. The organic esters and salts of esters of the boron acids hereof are very effective when used in combination with the sulfamic acids and sulfamates, e. g. N-alkyl sulfamic acids, e. g. N-methylsulfamic, N-ethylsulfamic, N-propylsulfamic, N-diethylsulfamic, N-dimethylsulfamic, etc., acids.

The addition of small quantities of other acids, such as tartaric, fumaric, malic, maleic, lactic, glycolic, glycerophosphoric, propionic and butyric may be resorted to. The lithium, sodium, potassium salts of these acids, as well as any of the above acids may be used as a source of the acid ions. The water-soluble salts of the sulfamic acids herein described such as the sodium, potassium, lithium, ammonium, aluminum, etc. salts are very useful. The salts of citric, tartaric, 30 boric, succinic, malic and maleic acids which have 2 or 3 ionizable sodium or potassium groups are generally more effective than those acids which yield a single sodium or potassium ion such as sodium acetate.

The compositions of this invention are useful for fixing baths which are of general utility in the photographic arts. Thus, they may be utilized for processing ordinary camera film, cinema film, multi-layer film, radiographic film, 40 including dental and medical X-ray film; lithographic film and other types of films and plates. The use of a concentrated solution of the correct ingredients for a photographic fixing bath greatly simplifies the mixing of such baths from the 45 standpoint of the consumer. However, for economic reasons, it is imperative that the water used to prepare the solutions should be kept at a minimum or in other words that the solution be as concentrated as possible. At the same time 50 it is necessary to make sure that a slight lowering of the temperature or some similar physical factor will not induce crystallization or precipitation.

One of the most important advantages of the 55 invention resides in the fact that it permits the preparation of concentrated fixing solutions containing more than 60% by weight of dissolved solids. A further advantage is that stable solutions of such concentrations can be prepared 60 for the trade without danger of the dissolved material crystallizing out of solution during storage or shipment. A still further advantage is that the invention permits the stabilization of highly concentrated solutions of ionized compounds against precipitation.

As many apparently widely different embodiments of this invention may be made without departing from the spirit and scope thereof, it is to be understood that I do not limit myself 70 to the specific embodiments herein, except as defined by the appended claims.

I claim:

1. A fixative composition comprising an aqueous solution containing a soluble thiosulfate fix- 75

ing salt and at least one ester of a boric acid with a polyhydric alcohol having at least 6 carbon atoms and 6 hydroxyl groups.

2. A fixative composition comprising a concentrated solution containing a thiosulfate fixing salt and at least one ester of a boric acid with a polyhydric alcohol having at least 6 carbon atoms and 6 hydroxyl groups.

3. A fixative composition comprising a concentrated aqueous solution containing a soluble thiosulfate fixing salt and at least one ester of a boric acid with a polyhydric alcohol having at least 6 carbon atoms and 6 hydroxyl groups on different carbon atoms.

4. A fixative composition comprising a concentrated aqueous solution containing a soluble thiosulfate fixing salt, a protein hardening agent, a preservative, an acid and an ester of a boric acid with a polyhydric alcohol having at least 6 carbon atoms.

5. A fixative composition comprising a concentrated aqueous solution containing a soluble thiosulfate fixing salt, a protein hardening agent, a preservative, an acid and an ester of a boric acid with a polyhydric alcohol having at least 6 carbon atoms, and at least 6 hydroxyl groups.

6. A fixative composition comprising a concentrated aqueous solution containing a soluble thiosulfate fixing salt, a protein hardening agent, a preservative, an acid and an ester of an orthoboric acid with a polyhydric alcohol having at least 6 carbon atoms, and at least 6 hydroxyl groups.

7. A concentrated aqueous photographic fixing bath containing more than 60% by weight of active ingredients comprising essentially an acid, soluble thiosulfate and soluble salt of sulfurous acid and at least one ester of a boric acid with a polyhydric alcohol having at least 6 carbon atoms in an amount sufficient to prevent the precipitation and crystallization of the ingredients.

8. A concentrated aqueous photographic fixing bath containing more than 60% by weight of active ingredients comprising essentially an acid, soluble thiosulfate and soluble salt of sulfurous acid and at least one ester of a boric acid with a polyhydric alcohol having at least 6 carbon atoms and at least 6 hydroxyl groups in an amount sufficient to prevent the precipitation and crystallization of the ingredients, at 40° F.

9. A concentrated aqueous photographic fixing bath containing more than 60% by weight of active ingredients comprising essentially an acid, soluble thiosulfate and soluble salt of sulfurous acid and not less than 8% by weight of at least one ester of a boric acid with a polyhydric alcohol having at least 6 carbon atoms.

10. A composition as set forth in claim 9 wherein said ester is a neutral ester.

11. A composition as set forth in claim 9 wherein said ester is a basic salt of an acid ester.

12. A fixative composition comprising an aqueous solution containing a soluble thiosulfate fixing salt and at least one ester of a boric acid with a hexitol.

13. A fixative composition comprising a concentrated aqueous solution containing a soluble thiosulfate fixing salt, a protein hardening agent, a preservative, an acid and an ester of a boric acid with a hexitol.

14. A concentrated aqueous photographic fixing bath containing more than 60% by weight of active ingredients comprising essentially an acid and a soluble thiosulfate fixing agent and at least one ester of a boric acid with a hexitol

in an amount sufficient to prevent the precipitation and crystallization of the ingredients, at 40° F.

15. A concentrated aqueous photographic fixing bath containing more than 60% by weight of active ingredients comprising essentially an acid and a soluble thiosulfate fixing agent, not

less than 8% by weight of at least one ester of a boric acid with a hexitol.

16. The process which comprises fixing a photographic element in a bath of the type defined by claim 1.

CHARLES HOLZWARTH.
